(57) **CLAIM**

The ornamental design for a dog ear lifter, as shown and described.

DESCRIPTION

FIG. 1 is a top, front, perspective view of a dog ear lifter showing my new design;

FIG. 2 is a front elevational view thereof, the rear view being a mirror image thereof;

FIG. 3 is a left side elevational view thereof, the right side view being a mirror image thereof;

FIG. 4 is a top plan view thereof; and,

FIG. 5 is a bottom plan view thereof.

1 Claim, 2 Drawing Sheets
